UNITED STATES PATENT OFFICE.

LOUIS F. EISELE, OF PHILADELPHIA, PENNSYLVANIA.

FIREPLACE GUARD SCREEN.

Application filed May 29, 1920. Serial No. 385,189.

To all whom it may concern:

Be it known that I, LOUIS F. EISELE, a citizen of the United States, residing at Philadelphia, in the county of Philadelphia and State of Pennsylvania, have invented certain new and useful Improvements in Fireplace Guard Screens, of which the following is a specification.

One object of my invention is to provide an improved rolling guard screen which can be used in connection with an open fireplace for the purpose of preventing sparks from flying out of the fireplace.

It is usually the custom to place an independent guard screen in front of the fireplace. These independent screens are undesirable for the reason that they must be carried into and out of position, take up a large amount of space in the front of the fireplace and are usually unsightly in appearance.

Another object is to so construct my improved guard screen that it can be installed in an open fireplace in such manner that when not in use it will be invisible from the outside of the fireplace, and when in use only the screen proper and the hand-holds will be visible.

A further object is to so make my guard screen that all of the parts can be easily installed without detriment to or change of the fireplace structure.

A still further object is to provide and so arrange the parts of my improved guard screen that the screen proper can be easily and quickly moved into and out of position.

Another object is to make my improved guard screen of a simple and durable construction and so that it can be quickly and easily manufactured and installed.

These objects, and other advantageous ends which will be described hereinafter, I attain in the following manner, reference being had to the accompanying drawings in which

Figure 1 is a front elevation of a fireplace provided with a guard screen made in accordance with my present invention,

Figure 2 is an enlarged elevation, partly in section, showing various parts of my improved guard screen such as that disclosed in Figure 1,

Figure 3 is a section taken on the line 3—3 of Figure 2,

Figure 4 is a sectional plan view taken on the line 4—4 of Figure 2,

Figure 5 is a fragmentary elevation showing the means of connection of the screen proper with the roller,

Figure 6 is a perspective view of a counter-balance weight which forms a part of my invention and which includes a hand-hold or a handle as a rigid part thereof, and

Figure 7 is a fragmentary perspective view showing a part of a guiding structure employed for the screen and counter-balance weight.

Referring to the drawings, 8 represents a fireplace including an opening 9 for containing the fire and the front of the fireplace includes a facing 10 which may be made of any suitable material out of which the facing of fireplaces is made, such for example as tiles, brick, marble or the like. Immediately to the rear of the facing 10 I provide a supporting structure for the guard screen; said supporting structure including two hollow uprights 11 and 12 which may be made in the shape indicated in Figures 2, 3, 4 and 7 preferably of heavy sheet metal. Each of the uprights 11 and 12 includes a channel section 13 having a cover 14. Each of the covers 14 has an indented portion 15 providing an upright groove 16 forming a guideway for the edge portion of a flexible screen 17. The uprights 11 and 12 are positioned immediately to the rear of the upright portions of the facing 10 at opposite sides of the opening 9 so that the uprights are not visible viewed from the front of the fireplace. The screen 17 is adapted to extend entirely across the opening 9 and the upper portion of the screen is secured to a hollow roller 18 preferably by means of a strip 19 as shown in Figure 5; said strip being secured to the roller by screws 20 or other suitable means. Heads 21 are inserted in opposite ends of the rollers and are free to rotate on trunnions or short stud axles 22 which are secured in extensions 23 of the uprights 11 and 12. The heads 21 are preferably secured by screws such as shown at 24 so that the heads may be readily attached and detached if desired. The trunnion 22 at one end is preferably made longer than the opposite trunnion as shown in Figure 2 and a ring or disk 25 of comparatively great diameter has pins 26 which fit within holes

100
105

in one of the heads. These pins also project into holes in a winding pulley 27; said winding pulley being positioned between the disk 25 and the extension 23 of the upright 12. 5 Thus the disk 25 provides a large flange for the winding pulley 27 and a chain 28 has its upper end secured to the winding pulley and its lower end secured to a counter-weight 29. The counter-weight 29 is adapted to slide 10 upwardly and downwardly within the upright 12 between the inner part of the indented portion 15 and the surface 30 of the channel section 13 as clearly shown in Figure 4. The cross-section of the counter-weight is preferably such that while a free sliding effect is insured, there will be practically no room for the weight to turn within the space as above described. The cover 14 of the upright 12 has a vertically extending slot 31 and an integral handle or hand-hold 32 projects outwardly from the body portion of the weight through the slot 31 a sufficient distance to permit a person to grasp the same for a purpose hereinafter described. The weight 29 substantially counter-balances the screen 17 and when the screen 17 is pulled downwardly to close the opening 9, the chain 28 will be wound on the winding pulley 27 between the disk 25 and the extension 23 of the upright 12.

Hoods 33 project toward each other from the extensions 23 of the uprights and form a protection for the various parts at the ends of the roller and an anti-friction roller 34 is 35 preferably provided as a guiding means for the chain 28 as clearly shown in Figure 3.

By providing the above structure the uprights can be made comparatively narrow and sufficient protection is provided for the parts adjacent the ends of the rollers. The upright 12 provides a casing for the weight 29 and for the flexible connection or chain 28 and at the same time provides guiding means for one edge of the screen 17.

45 By the above construction it is an easy matter to raise the screen and cause the latter to be wound upon the roller since it is merely necessary to exert a slight pressure downwardly upon the handle 32. This action will cause the chain 28 to rotate the roller so as to wind up the screen and in view of the construction of the upright 12 and weight 29, the latter will slide freely with practically no vibration. If it is desired to move the screen into a closing position, said screen may be pulled directly downward by pulling downwardly on the handle 33' or if desired the handle 32 can be raised and the weight of the screen will cause

50 the free edge thereof to descend into closing position. Furthermore the arrangement is such that the uprights and roller will be hidden back of the facing 10 of the fireplace as indicated by the dotted lines in Figure 1.

65 While I have described my invention as

taking a particular form, it will be understood that the various parts of my invention may be changed without departing from the spirit thereof, and hence I do not limit myself to the precise construction set forth, 70 but consider that I am at liberty to make such changes and alterations as fairly come within the scope of the appended claims.

Having thus described my invention, what I claim as new and desire to secure by Let. 75 ters Patent is:—

1. A fireplace of the character described including a rotatably mounted roller; a screen adapted to be wound upon said roller; an upright structure providing a guideway 80 for said screen and having a slot therein at a position leading from the side of said guideway; a counter-balance weight slidably fitting said guideway; a winding member rotatable in conjunction with said roller; 85 and a flexible connection for said weight and adapted to be wound on said winding member, said weight having a handle projecting therefrom outwardly through said slot and parallel with said screen in the guideway; 90 substantially as described.

2. A fireplace of the character described including a structure having a transversely extending portion and two hollow uprights spaced apart and jointly providing an opening, said uprights including channel sections having covers at their sides providing an enclosed chamber, said covers having indented portions projecting into said chambers and spaced from the front of the channel sections and providing upright grooves in the opposed sides of the uprights, the cover of one of said uprights having a slot leading out of the space between its indentation and the front of the adjacent channel; a roller mounted in the back of said transverse portion; a screen; and a flexible device wound on said roller, said flexible device extending down through the chamber of said latter mentioned upright, said screen being adapted to be pulled down with its opposed side edge portions within said upright grooves to close said opening; and a weight attached to said flexible device and slidably fitting between said indentation and the side of said latter channel, said weight having a rigid handle secured thereto and extending out through said slot in a position parallel with the screen in said upright grooves; substantially as described.

3. A device of the character described including a supporting structure providing opposed trunnions; a roller; a screen secured to the roller and adapted to be wound thereon; heads secured to the ends of said roller and providing holes eccentric to the axis of said roller; a winding pulley rotatably mounted on said trunnions; pins extending from said pulley into said holes; a counter-balance weight; flexible connecting means.

cured to said weight and adapted to be wound upon said pulley; and a disk of comparatively large diameter interposed between said pulley and the adjacent head of 5 the roller, said disk having holes through which said pins extend; substantially as described.

In testimony whereof I have signed my name to this specification in the presence of two subscribing witnesses.

LOUIS F. EISELE.
